UNITED STATES PATENT OFFICE.

MARY F. BISHOP, OF PHILADELPHIA, PENNSYLVANIA.

MOISTENER FOR ENVELOPS, POSTAGE-STAMPS, &c.

1,235,644.

Specification of Letters Patent.

Patented Aug. 7, 1917.

Application filed May 2, 1917. Serial No. 165,921.

To all whom it may concern:

Be it known that I, MARY F. BISHOP, a citizen of the United States, and residing at the city of Philadelphia, county of Philadelphia, and State of Pennsylvania, have invented certain new and useful Improvements in Moistener for Envelops, Postage-
5 Stamps, &c.; and I do declare the following to be a full, clear, and exact description of the invention, such as will enable others skilled in the art to which it appertains to make and use the same.

This invention relates to certain new and useful improvements in a moistener for
15 envelops, and it consists in a rotary holder for a brush or sponge that is adjustably mounted on a flexible drive shaft, for being immersed in a liquid bath and subsequently secured above the latter whereby an envelop, or other article, may be moved under
20 the brush and in contact therewith to be moistened thereby.

The primary object of this invention resides in an improved moistener or applicator which is mounted for movement into and from a liquid container and rotated or set in motion while an envelop or the like is moved across and in contact therewith.

The invention further resides in the features of construction and the arrangements and combinations of parts hereinafter described, claimed and illustrated in the accompanying drawing wherein—

Figure 1 is a vertical section through the preferred embodiment of the invention, portions being left in elevation; and

Fig. 2 is a similar view illustrating the modification of the invention, the well being adjustable vertically on its support.

Referring more in detail to the drawing, the numeral 1 designates the base having its upper surface forming a flat table 2 in which is formed an opening 3 having a counter bore for the reception of the marginal flange 4 of a removable well 5. The base is preferably hollow for lightness and the marginal flange or shoulder 4 therefore suspends the well in the hollow chamber of the base.

At a suitable distance from the well opening 3, the upper face of the base is formed with a second opening in which is disposed a case 6 that receives support on the bottom of the base chamber and houses a motor, either of the mechanical type, as a spring motor, or of the electrical type, in which

latter instance suitable current wires (not shown) are provided. Fixed on the case 6 is a goose-neck tubular housing 7 that has its shorter arm 8 terminating directly over the well 5, and through this housing is passed the flexible shaft 9 which has connection with the motor at one end and has its opposite end extended beyond the housing or tubular support for connection with a sponge or brush.

The numeral 10 indicates a sleeve that is vertically adjustable on the projecting free end of the flexible shaft, a set screw 11 being carried by the sleeve to be set against the shaft for holding said sleeve in a predetermined position. The lower end of the sleeve is formed with an enlargement 12 in which is secured a sponge or absorbent body 13.

In practice, the well is filled with water, if it is desired merely to moisten a surface already having a mucilaginous film dried thereon, or glue or paste, if it is desired to apply an adhesive to a surface. The screw 11 is loosened and the sleeve dropped to immerse the sponge in the bath contained in the well, after which the sleeve is elevated to the desired height and fixed in said adjustment by tightening the set screw. The 80 motor is now started to rotate the sponge as an envelop is shifted therebeneath over the broad flat surface afforded by the table 2.

The modified form of the invention comprises a motor case 14 which constitutes the supporting base and from which rises the goose-neck tubular support 15 for housing the flexible motor shaft 16, the latter having the sleeve 10 adjustably secured thereon by screw 11. The well 17, in this instance, is cup-shaped and has a flat top 18 constituting a broad supporting table for the envelop, said top having a central opening 19 through which the sponge 13 is lowered 100 for immersion in the bath. The well is adjustable up and down the longer arm of the tubular support by means of the ring clamp 20, carrying the well, and set screw 21.

In either form, the envelop is afforded a broad support over which it is shifted under the rotating sponge, the latter, through its rotary rubbing action, thoroughly moistening the dried mucilaginous film to effect perfect adhesion.

The terms "envelop" and "moistener" have been used herein in their broader

meanings for ease in description and clearness of understanding.

What is claimed is:

1. In a moistener for envelopes or the like, 5 a supporting base having a flat table, an open well supported within said table and below the plane thereof, a motor within said base, a tubular goose-neck support rising from the motor and terminating directly 10 over the well, a flexible motor shaft housed by the tubular support and extending beyond the free end of the latter, a sleeve adjustable on the projecting end of the shaft, and an absorbent body carried by the lower 15 end of the sleeve.

2. An envelop moistener, comprising a flat table, a well arranged beneath the table,

a tubular upright support having a return bend terminating directly over the well, a motor, a flexible motor shaft housed by the support and extending beyond the free end of the latter, a sleeve carried by the free end of the shaft, an absorbent body within the sleeve and depending therefrom, and means for adjusting said sleeve vertically whereby the absorbent body may be dipped into the well and elevated therefrom.

In testimony whereof I affix my signature in presence of two witnesses.

MARY F. BISHOP.
